UNITED STATES PATENT OFFICE.

HENRY A. WISE WOOD, OF NEW YORK, AND JOHN A. ISBELL, OF MIDDLETOWN, NEW YORK, ASSIGNORS TO WOOD NEWSPAPER MACHINERY CORPORATION, OF NEW YORK, N. Y., A CORPORATION OF VIRGINIA.

QUADRUPLE AIR-BRAKE FOR ROTARY PRESSES.

1,311,030.

Specification of Letters Patent.

Patented July 22, 1919.

Application filed April 29, 1916, Serial No. 94,459. Renewed December 26, 1918. Serial No. 268,419.

To all whom it may concern:

Be it known that we, HENRY A. WISE WOOD and JOHN A. ISBELL, citizens of the United States, said Wood residing at the 5 city, county, and State of New York, said ISBELL residing at Middletown, in the county of Orange and State of New York, have invented a new and useful Quadruple Air-Brake for Rotary Presses, of which the following is a specification.

This invention relates to a braking mechanism for rotary web printing presses.

The principal object of the invention is to apply brakes simultaneously to all of the 15 large moving members of a press or deck, that is, to the two impression and two printing cylinders, so as to prevent the braking strains usually coming from the sudden stopping of these heavy cylinders from being transmitted through the keys or the 20 teeth of the gears; also to provide a simple construction which will act quickly and reliably.

Reference is to be had to the accompanying 25 drawings, in which

Figure 1 is an end view of one deck of a rotary web press showing a preferred embodiment of this invention applied thereto, and

Fig. 2 is a sectional view of the same on the line 2—2 of Fig. 1.

The invention is shown as applied to a press having the usual frame 10, impression cylinders on shafts 11, and printing cylinders on shafts 12. In this type of press, power is transmitted through a gear 13 rotatable on the same axis as one of the impression cylinders meshing directly with another gear 14 of the same size but on the 35 same axis as another one of the impression cylinders. The gears 13 and 14 are on the back side of the machine. Each of the impression cylinder shafts is provided with a gear 16 meshing with another gear of the 40 same size on the printing cylinder shaft 12 and driving the printing cylinder at the same surface speed.

A hub 19 is keyed to each impression and printing cylinder shaft adjacent to the 45 smaller gear. This hub is provided with a brake band 20 in each case. One end of each brake band is adjustably connected by means of a screw 21 with the other end of the brake band of the cylinder of that pair.

The other end of each brake band is fastened 55 by a pin 22 to a link 23. This link is pivoted at its opposite end to the short arm of a lever 24. This lever is pivoted on a screw 25 on the frame 10 and its long arm is connected by a bolt 26 with means for operating 60 it. In the form shown one of the two levers 24 of this deck is connected by the bolt 26 with the head of a cylinder 27 while the other one is connected with the end of the piston rod 28. The piston rod is shown as 65 provided with a spring 29 seating against the opposite end of the cylinder. The cylinder is provided with means for introducing air or steam under compression in the form of a flexible pipe or hose 30 which is connected with the interior of the cylinder. 70

The operation will be obvious. Upon the introduction of air or steam under compression into the cylinder the piston and cylinder will be forced outwardly, but as neither 75 one is supported rigidly, one being carried by one lever 24 and the other by the other lever 24, the effect of this action is to turn both levers and to tend to turn them equally. But if one offers more resistance than the 80 other the one offering the smaller amount of resistance will be operated through a greater arc. The instant that either takes up all the looseness, it becomes for the time being a rigid member, and the other member is free 85 to exert pressure in the opposite direction. The braking effect on the two cylinders of each pair is equalized because the brake bands are connected by the bolt 21.

The braking operation therefore, although 90 performed simultaneously on all the impression and printing cylinders, takes effect in such a manner as to accommodate the conditions under which the press is being operated. As both the piston and cylinder are 95 free members the whole braking mechanism is equalized. By this quadruple braking system all the large moving members are slowed down simultaneously, but in a sense independently. The stopping strains are 100 equalized and the four cylinders of the deck are allowed to come to an even stop. The braking strains are not transmitted through the keys or the teeth of the gears as is the case where a whole deck or even half a deck 105 is stopped by one brake.

Although we have illustrated and described only a single embodiment of the in-

- vention and shown it as applied to a single type of press, we are aware of the fact that modifications can be made therein and that it can be applied to other types of presses without departing from the scope of the invention as expressed in the claims. Therefore we do not wish to be limited to all the details of construction herein shown and described, but what we do claim is:—
10. 1. The combination with two cylinders, of a brake hub for each of said cylinders, a pair of brake bands for said hubs, freely movable means for connecting one end of each band with one end of the other band, and means for simultaneously operating the other end of each band to apply the brakes.
2. The combination with two cylinders, each having a brake hub and a brake band for each hub, one end of each band being movably connected with the end of the other band, of means for connecting the other ends of each of the two bands, and means for simultaneously moving the free ends of the two bands together for the purpose of applying the brakes simultaneously and equally to the two hubs.
3. The combination with a printing and impression cylinder in contact with each other, each having a brake hub and a brake band for each hub, one end of each band being adjustably connected with the end of the other band, the free ends of the two bands being connected together, and a lever for simultaneously moving said free ends in the same direction to apply the brakes to the two hubs.
4. The combination with two printing and two impression cylinders of a printing press

deck, of a brake hub on each printing and impression cylinder, a brake band for each of said hubs, a pair of levers for operating the four brake bands, and means for operating the several brakes simultaneously.

5. The combination with the printing and impression cylinders of a printing press deck, of a brake hub on each printing and impression cylinder, a brake band for each of said hubs, a pair of levers for operating the brake bands, and means for operating the several brakes simultaneously, said means comprising a piston and cylinder, one connected with one lever and the other with the other lever.

6. The combination with the two impression and two printing cylinders of a printing press deck, of a brake hub for each cylinder, a brake band for each hub, one end of each of the two brake bands of each pair of impression and printing cylinders being connected together, a pair of levers, the short arm of each of which is connected with the two free ends of one pair of brake bands, a cylinder pivotally connected with the other arm of one of said levers, a piston therefore pivotally connected with the other lever, whereby said piston and cylinder are supported by said levers, and means for introducing pressure into the cylinders to actuate the piston and cylinder with respect to each other for the purpose of applying brakes simultaneously to all the four cylinders of the deck.

In testimony whereof we have hereunto set our hands.

HENRY A. WISE WOOD.
JOHN A. ISBELL.
